TUBE BENDING TOOL

Carroll E. Adreon, Baltimore, Md., assignor to The Glenn L. Martin Company, Middle River, Md., a corporation of Maryland

Application November 3, 1943, Serial No. 508,780

3 Claims. (Cl. 153—40)

1

This invention relates to a device for bending tubes about a predetermined radius of curvature for a selected number of degrees bend.

The difficulties encountered in bending small tubes accurately to a predetermined radius and for a definite angle between the ends of the tube, is well known. The problem is further involved when metals, such as the aluminum alloys, are employed. With ordinary bending, such tubes collapse, thus altering their cross-sectional area and causing a restriction to the flow of fluid therein and very often the tubes crack along the edges of the collapsed portion if any attempt is made to straighten them.

By this invention, a means is provided for bending tubes and accurately forming the radius curvature of the bend.

Another object of this invention is to afford a means for maintaining a definite angle of bend in the tube.

A further object of this invention is the prevention of the collapse or the alteration of the cross-sectional area of the opening in the tube while being bent.

Further and other objects will become apparent from the description of the accompanying drawings which form a part of this disclosure and in which like numerals refer to like parts.

In the drawings:

Figures 1 to 4 show the relationship of the parts of the tube bending tool during the bending operation.

Figures 5 to 8 show the operation of the cam mechanism and the relative position of the parts during the bending operation shown in Figures 1 to 4.

Figure 9 is a sectional view through the tube bending tool device.

The tube bending tool illustrated in the drawings comprises a base member 1 having a cavity 2 formed in the underside thereof. The base is formed with lugs 3, each having a hole 4 for mounting the tool on a bench. On top of block 1 are assembled the parts for holding and bending a tube. Rigidly secured to block 1 is bracket 5 to which forming die 6 is securely fastened. Retaining member 7 is also secured to bracket 5. Groove 8 in member 7 and groove 9 in die 6 are formed with a radius equal to the outside radius of the tube to be bent. Handle 10 passes through die 6 and bracket 5 and turns freely in each member. Portion 11 of handle 10 is square, while the remaining portion 12 is round and free to turn in block 1. Spring 13 is secured to the end of the handle within cavity 2 and to the block in such

5 a manner that the handle, when free, will be moved by the spring in a counter-clockwise direction in Figures 1 to 4. Forming block 14 has a portion 15 which extends under bracket 5 and is retained thereby between portion 16 of bracket 5 and the base 1. The configuration of cam member 18 is shown in Figures 5 to 8. This cam has a square hole formed therein, and fits over square portion 11 of handle 10, shown in Figure 9. Portion 15 forms a follower for cam 18 to move the forming die 14. The hole 17 formed in member 15 is shaped to cause forming die 14 to move radially inwardly, shown in Figure 6, when handle 10 is moved from the position shown in Figure 5 to that of Figure 6. A more detailed description of this action will be given subsequently.

20 An inspection of Figures 1 to 4 and 9 will show the relationship of the parts and their assembly. Member 6 is secured to portion 16 of bracket 5. This sub-assembly and block 7 are rigidly secured to the base. Cam 18 is placed in hole 17 of the follower 15, and the square hole 19, of the cam, is aligned with the holes in die block 6 and member 16. Handle 10 is then placed in the aligned holes until the square portion 11 engages the square hole 19. Washer 20 and spring 25 13 are then assembled on the portion of the handle extending within the cavity 2. Washer 20 is secured to portion 12.

As shown in Figures 1 to 4, a tube 21 is placed in groove 8 in retainer block 7. Since forming block 14 is spaced from the die block 6, the tube extends through this space and when held against block 7, lies substantially tangent to die 6. From an inspection of Figures 1 and 5, it will be apparent that as handle 10 moves in a clockwise direction to the position shown in Figures 2 and 6, cam 18 will move follower 15 so that forming block 14 moves radially inwardly, with index 22 aligned with the zero on die 6. The groove in the die and the groove in forming block 14 are such that they engage tube 21 with a sliding fit. Further clockwise motion of handle 10 as shown in Figures 3 and 7, will cause forming block 14 to move around die 6, and form the tube to the radius of curvature of the die. The angularity of the bend may be read in degrees. Counter-clockwise motion of handle 10, as shown in Figures 4 and 8, will release the forming block from engagement with the tube and die before returning the forming block to its initial position. Since the spring is so arranged that it urges the handle in a counterclockwise direction, when the desired degree of bend has been reached, the handle may be released by the operator and the

spring will first move block 14 radially outwardly to disengage the tube, and then return it to its initial position.

In the softer metal alloy tubes, the bend can be quickly and accurately effected as there is no spring-back in the metal and due to the fact that the circumference of the tube is limited at all times during the bending operation by the cooperation in the die and the forming block, the tube will not collapse and the cross-sectional area of the hole in the tube will not be altered.

If the tube is of a material, such as brass or steel, wherein there may be a slight spring-back, to form such a tube to an accurate bend, it is merely necessary to release the forming block slightly when the index 22 is aligned with the desired number of degrees and check the tube to see if it springs at that point. If it does, a few more degrees of bending may be necessary so that the tube will spring back to the proper angular position. The bend of the tube may be checked after the bending operation as described above.

Several types of cam action to give a similar motion of the die block may be employed but the preferred form herein described has been found to be simple in construction and sufficiently rugged to withstand continuous usage.

It will be noted that the base member is of such a height that there will be sufficient clearance, between the bench top on which the tube bending tool will be mounted, for the hands of the operator in manipulating the tubing in the tool.

It is to be understood that certain changes, alterations, modifications and substitutions can be made without departing from the spirit and scope of the appended claims.

I claim as my invention:

1. A tube bending tool comprising a base, a handle pivoted in said base, a cam member fixed to said handle, a plate mounted on said base having an opening formed therein surrounding said cam, said opening formed to provide a follower for

said cam, a curved die block concentric with the pivot of said handle having a groove around the periphery thereof, a retaining means to hold said tube in the initial position tangent to said die block, a forming block having a groove therein secured to said plate for movement therewith, said forming block spaced from said die block to allow the insertion of a tube to be bent whereby handle pivoting movement in one direction sequentially moves said plate and forming block radially of said die block to the tube engaging position and thereafter moves said die block bodily therewith to effect tube bending about the axis of said handle.

2. A tube bending tool comprising a base, a handle pivoted on the base, a curved die block fixed to said base, a tube restraining member fixed to the base in spaced relation to said die block, a cam fixed to said handle, a cam follower having an opening surrounding said cam, said opening being elongated radially of the handle axis whereby handle-pivoting movement sequentially moves the cam follower radial of the handle and thereafter bodily therewith about the axis of said handle and a tube engaging forming block fixed to said cam follower, the movement of which effects the bending of a tube about said die block.

3. A tube bending tool comprising a base, a handle pivoted on the base, a curved die block fixed to said base, a tube restraining member fixed to the base in spaced relation to said die block, a cam fixed to said handle, a cam follower having an opening surrounding said cam, said opening being elongated radially of the handle axis whereby handle-pivoting movement sequentially moves the cam follower radial of the handle and thereafter bodily therewith about the axis of said handle and a tube engaging forming block secured on one side only to said cam follower, the movement of which effects the bending of a tube about said die block.

CARROLL E. ADREON.
